PICTURE FRAME BANK

Edwin E. Stawniak and Edward Roman,
Taunton, Mass.

Application March 24, 1955, Serial No. 35,193

Term of patent 14 years

(Cl. D34—11)

FIG. 1.

FIG. 2.

FIG. 3.

We claim:

The ornamental design for a picture frame bank, as shown.
